UNITED STATES PATENT OFFICE.

LOUIS KYSER AND ALFRED C. REX, OF PHILADELPHIA, PENNSYLVANIA.

TOY SCALES.

SPECIFICATION forming part of Letters Patent No. 252,608, dated January 24, 1882.

Application filed June 27, 1881. (No model.)

To all whom it may concern:

Be it known that we, LOUIS KYSER and ALFRED C. REX, both of the city and county of Philadelphia and State of Pennsylvania, have 5 invented an Improvement in Toy Scales, of which the following is a specification.

Our invention relates to toy scales; and it consists in a novel construction of a small cast-iron scales, whereby the same is cheap to man- 10 ufacture, and also accurate in its weighing, said construction being fully set out in the following specification and shown in the accom- 15 panying drawings, which form part thereof.

In the drawings, Figure 1 is a sectional elevation of our improved toy scales on line *x x*. Fig. 2 is a cross-sectional elevation of same on the line *y y*.

A is the stand, and consists of the base or bed plate B, which is cast hollow, and provided 20 at the middle with an upright or standard, C, having a slot, E, at the top, and at the ends with wide holes D. Cast in the bed-plate or standard is a wire, H. A plate, I, provided with lugs J, fits in the bottom of the bed-plate 25 B and covers it up, and is held in position by the lugs J and the wire H, which is passed through the hole H' and bent over, as shown. This plate I is also provided with a hole, K, at either end, said holes being very slightly 30 larger than the rods S.

The lever L is provided at the center with a knife-edge, M, which works in slot E in the standard C, and is kept in place by a cap, F, which is secured to the standard by riveting 35 a wire, G, cast in said standard. Either end of lever L is pivoted in two recessed blocks, O, which are closed on the bottom by plates P, which are riveted to them at Q. Each end of the lever L is in the form of a T, in which the 40 upper bar represents two knife-edges, N, which work on the upper sides of the recesses in the blocks O. These blocks are cast solid with the weight-pan R and the merchandise-basket U, which supports the tin pan T.

Projecting downward from the pan R and 45 basket U and between the blocks O are the hubs R', into which the wire rods S are cast. These hubs, striking the bed-plate, prevent the lever L being thrown much out of balance. The rods S work through the large holes D in 50 the bed-plate, and are guided by the holes K in the plate I.

Secured to the front of the bed-plate, and forming part of it, is a shelf or support, V, for the weights W.

Having now described our invention, what we claim as new, and desire to secure by Letters Patent, is—

1. In a toy scales, the combination of the bed-plate B, with its standard C, lever L, working in said standard upon knife-edge M and kept in place by cap F, said lever being provided on its ends with knife-edges N, pan R, and basket U, both provided with recessed blocks O, having the bottoms closed with 60 plates P, which are riveted thereto, and hubs R', to which are secured rods S, plate I, provided with lugs J and holes K and H', and held in place by wire H, passed through hole H' and bent over, substantially as shown and 65 described.

2. In a toy scales, the combination of the bed-plate B, standard C, provided with slot E, plate I, provided with holes K K and H', wire H, lever L, pans R and U T, and their 70 rods S, as and for the purpose specified.

3. In a toy scales, the pan R, cast solid with the recessed blocks O, the bottom of said blocks being covered with plates P, riveted thereto, as shown and described.

In testimony of which invention we hereunto set our hands.

LOUIS KYSER.
ALFRED C. REX.
